COMBINED SWITCH AND SOCKET FOR ELECTRIC LAMPS

Mario D'Angelo, West Hempstead, N. Y., assignor to Gilbert Manufacturing Co., Inc., Long Island City, N. Y., a corporation of New York

Application June 5, 1953, Serial No. 359,804

7 Claims. (Cl. 200—51.16)

The present invention relates to sockets for electric lamps and the like and particularly to a socket having a switch integral therewith.

More particularly still the invention relates to modifications of conventional combined switches and sockets which permit very simplified construction as well as simplified assembly and connection of the lamp to a common 2-conductor electric cord. The construction of the usual combined lamp socket and switch involves a multiplicity of small parts which are assembled with considerable difficulty making the sockets relatively expensive. In the present device the number of parts is much reduced and the assembly greatly simplified the lamp socket therefore being inexpensively manufactured.

In the connection of conventional electric sockets to conductor cords it has heretofore been necessary to cut, strip, and twist the wires of the cord, then disassemble the socket, and apply the conductors to the screw-type binding post in order to connect the wires thereto. Moreover, it has been necessary to supply some type of strain relief usually by knotting the cord within the socket cap. According to the present invention the greater part of this procedure is completely eliminated particularly the stripping, twisting and connecting of the wires and the knotting thereof to provide strain relief.

It is an object of the invention to provide an improved electric socket and switch capable of rapid assembly with ordinary 2-conductor electric wires.

It is another object of the invention to provide an improved electric socket and switch which eliminates the usual screw connectors for the connecting wires.

It is another object of the invention to provide an improved electric socket and switch which reduces the number of parts and the assembly operations required to a minimum and which permits the use of inexpensive and easily fabricated parts.

It is a still further object of the invention to provide an electric socket and switch construction which provides strain relief without necessitating any knotting of the electric cord or other usual modes of providing such relief, such for example as gripping members formed in the socket cap.

Other objects and features of the invention will be apparent when the following description is considered in connection with the annexed drawings, in which:

Figure 1 is a front elevation of a socket switch combination in accordance with my invention, the view being partly in vertical cross-section in order to show the construction and particularly the construction of the switch;

Figure 2 is a vertical cross-section, the section being taken on the plane at right angles to the section of Figure 1;

Figure 3 is a horizontal cross-section of the socket switch combination, the view being taken on the plane of the line 3—3 of Figure 2;

Figure 4 is a top plan view of the base portion of the switch housing member;

2

Figure 5 is a perspective view showing the form of the contact terminals;

Figure 6 is a bottom plan view of the intermediate portion of the housing which intermediate portion houses both the switch element and the contact terminals; and

Figure 7 is a perspective view of the switch operating and toggle members.

Referring now to the drawings, the socket switch combination of the present invention has an outer casing formed by a casing shell 10 and a cap 11. The casing shell 10 is formed with corrugations 12 placed along the upper edge thereof for cooperation with similar corrugations 13 on the lower edge of the cap 11. At diametrically opposite points the casing shell 10 is notched as indicated at 14 to provide for the operating buttons 15 of the switch and also to lock the interior parts against rotation with respect to the shell and cap. Within the socket shell 10 there is placed an insulating lining 16. Although in conventional sockets this lining extends for the full height of the casing shell 10, in the present instance, it is unnecessary and the socket lining 16 terminates at the base of the slots 14. Lining 16 surrounds the threaded metallic lamp base receiving member 17.

Fixed to the lamp base receiving member 17 is the lower switch housing member 18 which, as is seen clearly in Figures 1, 2 and 4, is a molded plastic disk having a groove 20 extending thereacross, this groove being relatively shallow and being intersected by a deeper groove 21. The groove 20 has inclined terminal ends, as shown clearly in Figure 1, and there is mounted for sliding movement in the groove the switch operating member 22 which has insulating buttons 15 at its ends. Member 22 has a depending central portion indicated at 23 and the upper surface of this depending portion is formed with the two prongs 24. The base member 18, in addition to being provided with the grooves 20 and 21, is provided with the slots 25 which slots are wider at the upper surface than at the lower surface as is clearly indicated in Figure 4.

Positioned in the groove 21 is the switch toggle member 26, this member being provided with a notch at 27, Figure 7, to accommodate the lower edge of the operating member 22. The groove 21 has bevelled edges and forms a pivot point for the member 26. Member 26 is formed with an opening 28, the margin having a depending portion 30 as is clearly shown in Figure 7. The usual toggle spring 31 extends from the depending portion 23 of the operating member 22 to the upper edge of the aperture 28 in the toggle member 26, the spring being held in position by the upwardly protruding prongs 24 on the member 22 and the downwardly protruding portion 30 of the member 26. The elements just described form a usual type of toggle switch arrangement, the spring tending at all times to elongate to its maximum extent and therefore causing the toggle member 26 to rotate about its pivot in the groove 21 as the switch operating member 22 is moved from side to side as seen in Figure 1.

Mounted on the base housing portion 18, just described, is an intermediate housing portion 32. This housing portion 32 is best shown in Figures 1 through 3 and 6. It is generally rectangular in shape and is hollow save for the two ends of the rectangle which are closed by the bottoms shown at 33. Each of the bottom portions 33 is provided with an aperture 34 for a purpose which will later appear. Additionally, the upstanding wall portions 35 are provided with inward projections designated as 36, see Figure 3 and, in addition, partition walls 37 are provided.

Centrally of the member 32 and formed integrally with the member are outwardly extending U-shaped portions 38 which are substantially half the height of the

member 32. The portions 38 serve as guides for the operating member 23 in its movement in the slot 20, the operating buttons 15 being of a size to substantially fit in the grooves which, of course, are closed by the base member 18 when the device is assembled. At one end the rectangular intermediate housing 32 is provided with a notch in its upper surface as shown at 40, Figure 3, this notch serving to accommodate a 2-conductor cord which is laid therein as will later appear.

The member 32 is also provided with outwardly extending flanges along its sides as shown particularly at 41, Figure 1, these flanges cooperating with inturned flanges 42 on a cap member 43, the cap member being a molded insulating member generally rectangular in shape and of substantially the same size as the top of the rectangular housing member 32 so that the cover completely closes the open top of member 32.

The inner wall of member 32 is provided near its left hand end with a pair of vertically extending grooves 44 and a terminal member 45, having the shape shown in Figure 5, is inserted in these grooves with the bent-over portion or ear 46 thereof extending to the left as seen in Figure 3. Member 45 is provided with two sharp prongs 48 at its upper edge and is provided with a slot or hole 50 in the ear 46. When the parts are assembled a rivet 51 extends through the slot 50, through the hole 34 in the base of the intermediate housing member 32, through a corresponding hole in the housing base 18, and thence through a hole in the turned-over flange 52 of the threaded lamp base receiving member 17. Adjacent the left one of the partitions 37 and to the left thereof vertically extending grooves 53 are formed in the opposite end walls of the member 32 and a terminal member 54 is inserted with its edges in the groove. This member 54 is shown in Figure 5 and comprises a straight portion having formed at the top thereof a laterally extending portion 55 which is bent in a return bend as clearly shown in Figure 5. Before the device is assembled the lower end 56 lies parallel with the remaining central portion. The terminal member is thus inserted into the groove and extends through the opening 57 in the base of the intermediate housing portion 32, thence through the corresponding opening 25 in the housing portion 18, and is then bent over, as shown clearly in Figure 2, to form the center contact for the electric lamp. It should be noted at this point that the partition 37 is notched at its upper edge to accommodate the laterally bent portion 55 of the terminal member 54.

The interior walls of the housing portion 32 are provided at the right of the center line, as seen in Figure 3, with grooves 58 similar to the grooves 53. In these grooves a terminal member 60, see Figure 5, is inserted, this member being provided with upstanding sharpened prongs 61 and being also provided with the laterally extending portion 62. The laterally extending portions 55 and 62 of the terminal members 54 and 60 respectively comprise contact members with which the toggle member 26 cooperates to form a switch. The upstanding prongs 48 and 61 of the terminal members 45 and 60 respectively serve to penetrate the two conductors of a 2-conductor cord shown at 63 in Figure 2 and to thereby connect the members to respective conductors. It will be noticed that when the device is assembled, as above described, the prongs 48 lie on one side of the center line and prongs 61 on the other side of the center line assuring that each set of prongs will cooperate with one, and only one, of the two conductors of a 2-conductor cord in which the two conductors are parallel to each other.

The assembly of the parts heretofore mentioned has been indicated in connection with the fastening of the terminal member 45 in its position. In addition to the rivet 51 which serves the function mentioned there is provided a similar rivet 64 which extends through one of the apertures 34 in the intermediate housing 32 and through corresponding holes in the housing member 18

and the flange of threaded lamp receiving member 17, thus fixing the parts firmly together.

As will be seen particularly by reference to Figures 1 and 2, the toggle member 26 extends upwardly into the central opening in the intermediate housing 32 in position to bridge across from the end of the return bend 55 of member 54 to the end of the return bend 62 of the terminal member 60, thus completing a circuit from one of the two conductors of the cord 63 through the terminal member 45, the rivet 51, the threaded lamp receiving member 17, the lamp filament, the central lamp contact 56, the terminal member 55, toggle member 26, the terminal member 60, to the other one of the pair of conductors in the 2-conductor cord 63. When the member 23 is operated to its other extreme position, that is, to the left as seen in Figure 1, the toggle member 26 will move away from the return bend portions of the terminals 45 and 61 and will lie against the partition wall of member 32, thus breaking the circuit just above described. The circuit open position is shown in full lines in Figure 1.

As has been indicated, the switch socket combination is connected to the cord by merely passing the cord through the central opening in the socket cap 11, then laying the cord in the groove 40 and extending toward the left as seen in Figure 2, with the end thereof bent down and into the hollow portion of the rectangular housing 32. After this has been done the cap 43 is placed on the housing member 32 and presses the cord 63 downwardly until the prongs 45 and 61 respectively penetrate through the cord insulation and make contact with the conductors. The insulating lining 16 is placed in the socket shell 10, the assembled switch and socket then placed within the insulating lining 16, as shown in Figure 1, and the cap 11 snapped onto the shell 10. It will be noted that because of the construction of the combined switch and socket, that is, because all of the exposed parts thereof are made of insulating plastic it is unnecessary that the lining 16 extend to the top of the shell 10 and also unnecessary that the cap 11 be provided with an insulating lining. This considerably reduces the cost of the completed switch and socket.

While I have described a preferred embodiment of my invention, it will be understood that I wish to be limited not by the foregoing description, but solely by the claims granted to me.

What is claimed is:

1. A switch socket for electric light bulbs comprising, in combination, an insulating housing structure, a metallic, threaded light bulb-receiving contact shell fixed on said housing structure, a conductor cord-receiving channel in said housing structure, a pair of switch terminals mounted in said housing structure, a toggle switch member pivotally mounted within said housing in position to bridge across said switch terminals, one of said switch terminals having an insulation piercing pointed end extending within said channel, the other of said switch terminals having an end thereof extending insulatingly within said contact shell and formed as a contact tongue for the center base terminal of a threaded base electric light bulb, a contact member having an insulation piercing pointed end extending within said channel at the side thereof opposite said insulation piercing end of said first switch terminal, the other end of said contact member being electrically connected to said contact shell, and a slidable cover piece for said channel, said cover piece engaging said insulating housing structure for pressing a conductor cord in said channel against the piercing ends of said switch terminal and contact member to pierce the insulation of said conductor cord and make contact with the conductors therein whereby connection is made between said wires and a light bulb threaded in said contact shell when said toggle switch member is in circuit closing position.

2. A combined socket and switch for electric light

bulbs comprising in combination, an insulating housing structure, a metallic, threaded light bulb-receiving contact shell fixed on said housing structure, said structure having a cord-receiving channel, a pair of switch terminals fixed in said housing structure, one of said switch terminals having an insulation-piercing pointed end extending within said conductor cord-receiving channel, a toggle switch member pivotally mounted within said housing structure, said member being adapted to bridge across said switch terminals, a switch-operating member slidably mounted within said housing structure, said operating member having its ends extending exteriorly of said housing structure, a toggle switch spring extending between said switch member and said operating member to operate said switch member to open and close the circuit through said terminals, the second of said switch terminals having an end thereof extending insulatingly within said contact shell and formed as a contact tongue for the center base terminal of a threaded base electric light bulb, a contact member having an insulation-piercing pointed end extending within said channel at the side opposite said insulation piercing end of said terminal, the other end of said contact member being electrically connected to said contact shell, and a slidable cover piece for said cord-receiving channel, said cover piece engaging said insulating housing structure for pressing a conductor cord in said channel on said switch terminal and contact member pointed ends to pierce the insulation of said conductor cord and make contact with the conductors therein whereby connection is made between said wires and a light bulb in said contact shell when said toggle switch member is in circuit closing position.

3. A switch socket for electric light bulbs comprising an insulating housing structure, said structure being composed of a base member, an intermediate member and a cap member, said intermediate member being generally rectangular in shape and having formed integrally therewith, a pair of extensions U-shaped in cross-section, said extensions extending perpendicular to the axis of said rectangular housing portion, said housing portion having a cord-receiving channel extending longitudinally thereof at its upper end and having a central opening extending therethrough and communicating with said cord-receiving channel, said intermediate housing member also having an opening communicating with said channel at each end thereof, said openings being closed at the bottoms thereof, a pair of switch terminals mounted in said intermediate housing, said switch terminals extending transversely of said housing adjacent said central opening, one of said switch terminals having a pronged upper end for piercing a cord conductor lying in said channel, said base housing portion having a slot extending diametrically thereof and a short slot extending perpendicularly to said first slot, a toggle switch member adapted to bridge said switch terminals, said switch member being pivotally mounted in said short slot in said base member and extending upwardly into the central opening of said intermediate member to make contact with said switch terminals, a switch operating member slidably mounted in said diametrically extending slot for reciprocation with respect to said base and intermediate body portions, said switch operating member being provided with insulating buttons at its ends, said buttons being guided in the said U-shaped portions of said intermediate housing, said switch operating member extending through an aperture in said toggle member, a spring extending between said switch operating member and said toggle member to cause said switch operating member to bear against said switch terminals when said switch operating member is in one position and to lie against a wall of said central opening in said intermediate housing when said switch operating member is in its other position, the second of said switch terminals having its lower end extending through said intermediate housing and said base housing and being bent over to form a contact for the center ter-

minal of an electric light bulb, a screw threaded light bulb-receiving contact shell mounted on said base housing, substantially concentric of said lamp contact, a contact member mounted in one of said end apertures of said intermediate housing, said contact member having an upper pronged end for piercing a conductor cord lying in said channel, said contact member having a lower end bent off and fixed to the bottom wall of said intermediate housing, said bent off portion being fastened to said light bulb receiving contact shell, and a slidable cover piece for said channel, said cover piece having downwardly extending and inwardly bent flanges thereon, said intermediate housing having outwardly extending flanges thereon, said flanges cooperating to hold said cover plate against the upper surface of said housing and to press a conductor in said channel on the pronged upper ends of said one switch terminal and said contact member to make contact with the pair of wires of the cord conductor lying in said channel.

20 4. A device as claimed in claim 3, characterized in that said switch terminals are provided with bent off portions extending toward each other and into said central opening of said intermediate housing to thereby cooperate with said toggle member.

5 5. A combined socket and switch for electric light bulbs comprising a casing having relatively separable cap and body portions, said body portion having diametrically opposite cutout portions, an insulating lining within said casing body portion and extending from the end opposite said cap portion to said cutout portions, and a switch and socket structure within said casing and said lining, said switch and socket structure comprising an insulating housing structure, a metallic, threaded light bulb-receiving contact shell fixed on said housing structure, a conductor cord-receiving channel in said housing structure, a pair of switch terminals mounted in said housing structure, a toggle switch member pivotally mounted within said housing in position to bridge across said switch terminals, one of said switch terminals having an insulation piercing pointed end extending within said channel, the other of said switch terminals having an end thereof extending insulatingly within said contact shell and formed as a contact tongue for the center base terminal of a threaded base electric light bulb, a contact member having an insulation piercing pointed end extending within said channel at the side thereof opposite said insulation piercing end of said first switch terminal, the other end of said contact member being electrically connected to said contact shell, and a slidable cover piece for said channel, said cover piece engaging said insulating housing structure for pressing a conductor cord in said channel against the piercing ends of said switch terminal and contact member to pierce the insulation of said conductor cord and make contact with the conductors therein whereby connection is made between said wires and a light bulb threaded in said contact shell when said toggle switch member is in circuit closing position.

60 6. A device as claimed in claim 5, characterized in that said casing cap has a cord aperture located on the axis of said socket, and said housing cord-receiving channel and cover extend perpendicularly to said axis whereby pull on said cord is taken up by said housing cover piece and no strain is placed on the switch terminal or contact member.

65 7. A switch socket for electric light bulbs comprising an insulating housing structure, said structure being composed of a base member, an intermediate member and a cap member, said intermediate member being generally rectangular in shape and having formed integrally therewith a pair of extensions U-shaped in cross-section, said extensions extending perpendicular to the axis of said rectangular housing portion, said housing portion having a cord-receiving channel extending longitudinally thereof at its upper end and having a central opening extending therethrough and communicating with said cord-receiving

ing channel, said intermediate housing member also having an opening communicating with said channel at each end thereof, said openings being closed at the bottoms thereof, a plurality of pairs of oppositely facing grooves in the interior wall of said intermediate housing member, a pair of switch terminals, each terminal being mounted in a pair of said grooves and extending transversely of said intermediate housing adjacent said central opening, one of said switch terminals having a pronged upper end for piercing a cord conductor lying in said channel, said base housing portion having a slot extending diametrically thereof and a short slot extending perpendicularly to said first slot, a toggle switch member adapted to bridge said switch terminals, said switch member being pivotally mounted in said short slot in said base member and extending upwardly into the central opening of said intermediate member to make contact with said switch terminals, a switch operating member slidably mounted in said diametrically extending slot for reciprocation with respect to said base and intermediate body portions, said switch operating member being provided with insulating buttons at its ends, said buttons being guided in the said U-shaped portions of said intermediate housing, said switch operating member extending through an aperture in said toggle member, a spring extending between said switch operating member and said toggle member to cause said switch operating member to bear against said switch terminals when said switch operating member is in one position and to lie against a wall of said central opening in said intermediate housing when said switch operating member is in its other position, the second of said switch terminals having its lower end
